UNITED STATES PATENT OFFICE.

JOHN A. WESER, OF NEW YORK, N. Y.; ELSIE L. WESER, ADMINISTRATRIX OF SAID JOHN ALBERT WESER, DECEASED, ASSIGNOR TO WESER BROS., INC., OF NEW YORK, N. Y., A CORPORATION OF NEW YORK.

MECHANICAL MUSICAL INSTRUMENT.

1,289,585.

Specification of Letters Patent. Patented Dec. 31, 1918.

Application filed January 3, 1917. Serial No. 140,438.

To all whom it may concern:

Be it known that I, JOHN A. WESER, a citizen of the United States, and a resident of the borough of Manhattan of the city of New York, in the State of New York, have invented certain new and useful Improvements in Mechanical Musical Instruments, of which the following is a specification, reference being had to the accompanying drawings, forming a part hereof.

This invention relates to mechanical musical instruments and is concerned particularly with the devices for actuating the wind-on roll and the carrier roll and the mechanism for controlling these devices.

The invention will be described herein-after with reference to the accompanying drawings in which is illustrated a preferred embodiment of the invention, and in which—

Figure 1 is a view partly in side elevation and partly in section of winding and rewinding devices embodying the present invention and showing the clutch of the wind-on roll in operative relation to its driven member.

Fig. 2 is a view similar to Fig. 1, but showing the clutch of the wind-on roll disengaged and the clutch for the carrying roll engaged.

Fig. 3 is a view in section taken on the plane indicated by the line 3—3 of Fig. 1 and looking in the direction of the arrows, the brakes for the wind-on roll and the carrying roll, respectively, being shown clearly.

Fig. 4 is a detail view in side elevation of the single controlling lever for the clutch and brakes shown in the other figures.

In Fig. 1 a fragment of the tracker box is shown at *a*, the supporting shaft for the carrier roll is indicated at *b* and the supporting shaft for the wind-on roll is indicated at *c*. These shafts are journaled in a suitable frame *d* cast integral and serving as a support for all of the elements which coöperate to bring about the winding and rewinding of the music sheet, as will appear from Fig. 2. On the shaft *c* and within the frame *d* is fixedly mounted a collar *e* adapted to be held in place by a set screw *e'* passing radially therethrough. The collar or clutch member *e* carries a spring-pressed clutch pin *e''*, the end of which projects beyond the side face of the collar and is

adapted to enter into recesses *f* formed in the proximate face of a clutch sleeve *f'* which is slidably mounted on the shaft *c*. The sleeve *f'* carries a spur gear *f''* which meshes with a driving pinion *g* fixed on a stub shaft *g'*, which is also journaled in the frame *d* and may receive its power from any available source, as through a sprocket *g''* and chain *g'''* (the latter being indicated in dotted lines). It should be noted that the teeth of the pinion *g* are relatively elongated so as to permit the gear *f''* to be slid longitudinally thereof without becoming disengaged.

Referring now to the shaft *b* for the carrier roll it will be evident that the coöperating clutch elements *E* and *F'* with the pins *E''* and recesses *F* provided on the proximate faces of these elements, respectively, are substantially like the elements *e* and *f*, already described. However, a slight modification in the means for driving the shaft *b* by the power shaft *g'*, as during rewinding of the music sheet, is made. For instance, the sliding clutch sleeve *F'* is formed with a sprocket *F''*, engaged by a chain *h* which is in driving engagement with a sprocket *g''* formed on the hub of the pinion *g*. The tension of this chain *h* may be maintained automatically by an idler sprocket *i* carried loosely on a hinged arm *k* which is also journaled in the frame *d*. A spring for pressing the idler sprocket *i* against the chain *h* is mounted on the frame *d* and is indicated by the reference character *k'*. The frame *d* also carries a suitable bearing plate *l* for spring brakes *l'*, the braking surfaces of which may be formed of any usual wear resisting material, such as strips of leather, indicated at *l''*, and arranged to coöperate respectively with the peripheries of the clutch collars *e* and *E*. On the supporting plate *l* for the brakes *l'* is pivotally mounted, as at *m*, a clutch lever *n*, on the faces of which are fixed the studs *n'* and *n''* adapted to engage annular grooves *f'''* and *F'''*, respectively, formed in the clutch sleeves *f'* and *F'*. On one edge of the clutch lever *n* are secured beveled pins *n'''* and *n''''*, the beveled or conical faces of which are operatively disposed with respect to the brake springs *l'* so that when the lever *n* is rocked about its pivotal support *m*, one or the other

of the beveled pins n^3 or n^4 engages one of the brake springs l' and moves its brake shoe l^2 out of engagement with one or the other of the clutch collars e , E , as the case 5 may be. The means for rocking the lever n about its pivotal support m is illustrated in the accompanying drawings as comprising a rod o which may be reciprocated manually or otherwise to initiate operation of 10 the wind-on roll or the rewinding roll, as is now the general practice.

In operation, assuming that the carrier roll has been placed within the tracker box and has one end supported on the shaft b 15 and the music sheet has had its end engaged with the wind-on roll, one end of which will be journaled on the shaft c , and that it is desired to play the composition on the sheet, the controlling rod o will be moved to rock 20 the lower end of the lever n and slide the recesses f in the clutch sleeve f' into engagement with the pins e^2 on the clutch collar e . This movement of the lever n will move the beveled pin n^3 into engagement with the 25 lower brake spring l' , as indicated in Fig. 3, and thereby release the brake shoe l^2 from its engagement with the periphery of the clutch collar e . The accompanying movement of the upper end of the lever n will 30 serve to draw the bevel pin n^4 out of engagement with the brake spring l' thereby permitting the upper brake shoe l^2 to resume its engagement with the clutch collar E , and the clutch sleeve F' will be slid along the shaft b 35 out of engagement with the clutch collar. If the power is then applied to the actuating shaft g' , through the chain g^3 and sprocket g^2 , the wind-on roll will be rotated by reason of the engagement of the pinion g with 40 the gear f^2 and the engagement of the clutch elements, as before described. The clutch sleeve F' on the shaft b of the carrier roll will be rotated idly on the shaft and no power will be applied to the carrier roll. 45 To the contrary, the carrier roll will be rotated as the music sheet is drawn therefrom, against the braking action of the upper shoe l^2 . After the composition has been rendered, the sheet may be rewound on to the carrier 50 roll by manipulating the rod o in such manner as to rock the lever n and draw the lower clutch sleeve f' out of engagement with the clutch collar e , release the lower brake shoe l^2 so that it engages the clutch collar e , and 55 simultaneously move the upper beveled pin n^4 against the spring brake l' so as to release the shoe l^2 from its engagement with the clutch collar E and move the clutch sleeve F' into engagement with the clutch

collar E . From Fig. 2 it will be observed that this sliding movement of the collar F' serves to move the sprocket F^2 out of alinement with the sprocket g^4 , but the slack in the chain h and the slant thereof is always compensated for by the spring-pressed idler i .

From the above description it is thought that the improved features of the wind-on and rewinding devices will be fully appreciated and that their simplicity of construction, cheapness of manufacture and certainty of operation will constitute a marked improvement in the art.

Mechanical changes of the parts and rearrangements thereof may be made by those skilled in the art, but all such changes and rearrangements are to be deemed within the spirit of this invention provided they fall within the scope of the appended claims.

I claim as my invention:

1. In a mechanical musical instrument, winding and rewinding devices, comprising shafts for the carrier roll and the wind-on roll respectively, clutch elements carried on said shafts, said clutch elements including sliding sleeves, a gear carried on one of the sliding sleeves, a sprocket carried on the other sliding sleeve, an elongated power pinion in mesh with the said gear, a sprocket formed on the hub of said pinion, a chain operatively connecting the first named sprocket with the last named sprocket, an idler engaging said chain, and a spring-pressed arm on which the idler is mounted, whereby the tension of the chain is maintained regardless of the position of the first named sprocket with respect to the second named sprocket.

2. In a mechanical musical instrument, winding and rewinding devices including two sprocket wheels, a chain engaging said wheels, a sliding transmission gear, an elongated pinion with which the gear is engaged in all positions, two clutches each including collars and pins on one of said collars to engage recesses in the other of said collars, a straight brake spring in operative relation with the driven clutch members and a straight, pivoted reversing bar in operative relation with the sliding gear, the driving clutch members and the brake spring whereby the direction of rotation of the wheels may be changed without disengaging said gears.

This specification signed this thirtieth day of December 1916.

JOHN A. WESER.
